(57) CLAIM

The ornamental design for a skirt, as shown and described.

DESCRIPTION

FIG. 1 is a perspective view of a skirt, showing my new design;

FIG. 2 is a front elevation view thereof;

FIG. 3 is a rear elevation view thereof;

FIG. 4 is a left side elevation view thereof; and,

FIG. 5 is a right side elevation view thereof.

The broken lines shown in the drawings depict portions of the skirt that form no part of the claimed design.
